UNITED STATES PATENT OFFICE.

MARSHALL F. CAPRON, OF DETROIT, MICHIGAN.

MACHINE FOR ASSEMBLING METALLIC LINKS.

No. 821,782.

Specification of Letters Patent.

Patented May 29, 1906.

Application filed June 4, 1904. Serial No. 211,199.

To all whom it may concern:

Be it known that I, MARSHALL F. CAPRON, a citizen of the United States, residing at Detroit, county of Wayne, State of Michigan, have invented a certain new and useful Improvement in Machines for Assembling Metallic Links, of which the following is a specification, reference being had to the accompanying drawings, which form a part of this specification.

My invention has for its object to provide a machine for assembling metallic links, the same being more particularly designed for assembling standard malleable-iron links for chains such as are ordinarily used in the market.

The purpose of my invention is to provide a machine for this purpose of simple and economical construction by means of which the links may be quickly and efficiently assembled to form a chain.

My invention consists of the construction, combination, and arrangement of devices hereinafter described and claimed, and illustrated in the accompanying drawings, in which—

Figure 1 is a view in plan, illustrating my invention. Fig. 2 is a view in side elevation, showing parts broken away. Fig. 3 is an end view of a portion of the mechanism. Fig. 4 is a view in end elevation of parts looking from the opposite end of the machine. Fig. 5 is a view in vertical longitudinal section through parts of the mechanism. Fig. 6 is a view in vertical cross-section, through portions of the mechanism. Fig. 7 is a detail view of the cylinder with one end of the reciprocating slide. Fig. 8 is an end view of the cylinder. Fig. 9 is a vertical section through the slide and showing the cross-head. Fig. 10 is a detail view showing the push-bar and dog, parts being broken away. Fig. 11 is an end view of mechanism shown in Fig. 10. Fig. 12 is a detail view showing the position assumed by the links in assembling the same, and Fig. 13 is a plan view of one of the links.

My invention aims to feed the individual links through a suitable runway upon a bed or table, then forcing the link laterally a suitable distance to a guideway and at the same time into engagement with a link previously fed into a guideway, then forcing the links along said guideway by suitable mechanism to form a chain of desired length.

The machine is designed to work automatically.

I carry out my invention as follows:

In the drawings, *a* represents any suitable bed or support, and *b* denotes any suitable runway secured thereupon, through which the links may be fed, the runway being constructed to feed in a continuous manner any desired number of the links to the work in an upwardly-extended position. At one side of the runway is a guideway, (indicated at *c*.) To deliver a link from the base of the runway to the guideway, located at one side of the runway, I employ a reciprocating slide, (indicated at *d*.) which is preferably attached to a cross-head *e*, the cross-head being connected with an eccentric *f* upon a driving-shaft *g*. The opposite end of the slide *d* is preferably provided with a shoe *h* to engage the link to force the link over into the guideway *c*. This shoe is preferably constructed as indicated more particularly in Fig. 7. The shoe and adjacent part of the slide or rod *d* is made reciprocating through a cylinder *i*, engaged upon the bed *a*, the cylinder being cut away at one side and at one end to permit the link to drop in front of the shoe.

The links are shown at *j* with the hook *k* at one end thereof, and at one side the link is formed with a recess (indicated at *l*, Fig. 13) to permit the hook of an adjacent link to slide over the recessed side of the link, so as to engage the end of the adjacent link opposite its hook. The runway *b* is secured in any suitable manner upon the bed *a*. As will be seen, the same is cut away at one side, as indicated at *m*, so that the link may move in a corresponding direction into the guideway *c*, which extends at right angles to the movement of the slide *d*. The opposite side of the runway *b* is secured in any suitable manner upon the bed *a*. As will be seen, the same is cut away at one side, as indicated at *m*, so that the link may move in a corresponding direction into the guideway *c*, which extends at right angles to the movement of the slide *d*. The opposite side of the runway *b* obviously does not need to be so cut away, but extends downward to form a cap for the adjacent portion of the cylinder *i*. The shoe is cut away, as at *n*, so that the adjacent side of the link may bear against the hook *k*, the end of the link contacting with the extension *q* of the shoe. When a given link has been forced by the reciprocating shoe *h* into the path of the guideway *c*, a push-rod *r*, having an intermittent reciprocating movement, is moved to force the link into and along the guideway *c*. The inner end of the push-rod is provided with a swinging dog *s*, constructed to contact with the hooked portion of the link, and as the push-rod is

forced toward the guideway *c* the dog *s*, bearing against the hook of the link which has just been moved over into position from the runway, throws the link over into horizontal 5 position, as indicated, for example, in Figs. 5 and 12, while at the same time the link just engaged by the push-rod is being forced, with the link to which it is engaged, along the guideway *c*. The end of the dog *s* contacting 10 with the hooked portion of the link is preferably constructed with a curved point at its upper extremity, so as to fit somewhat over the correspondingly-curved portion of the hook of the link to aid in preventing the 15 link from tilting upward in the act of its being forced into position and along the guideway *c*. When the push-rod has done its work, in order that the dog may be returned to normal position it is necessary that it 20 should swing down out of working position, as indicated in Fig. 10. For this purpose I provide a spring *t*, bearing on the under surface of the dog, which may yield to allow the dog to return to normal position. When 25 pressure is relieved from the dog, the spring will restore the same to normal position. It will be observed that the forward end of the push-rod is cut away or recessed through one side to receive the inner end of the dog, which 30 is fulcrumed therein, the spring *t* being secured, preferably, on the under side of the push-rod, as shown.

Above the guideway *c* are friction-rollers, (indicated at *u*), the same preferably carried 35 by an arm *v*, fulcrumed at the end thereof opposite the rollers, as indicated at *w*. These rollers are constructed to bear upon the sides of the adjacent link, as shown, said rollers serving the double purpose not only in assisting 40 in holding the link down in horizontal position, but at the same time serving to prevent the chain from being drawn back with a backward movement of the push-rod. Any desired pressure may be given to the rollers 45 by means of a set-screw *x*. To give the desired movement to the push-rod *r*, I have shown an oscillatory lever *y*, suitably connected with said push-rod at one end of said lever, said lever being fulcrumed intermediate 50 of its extremities, as indicated at *z*. The lever may be actuated in any desired manner. As shown, the end of the lever opposite the push-bar is engaged in a cam-groove (indicated by the numeral 14) upon the driving- 55 shaft *g*. This cam-groove is constructed with a straight face (indicated at 35) extending a suitable distance thereabout, so that while the cam-roller on the end of the lever *y* is riding in the straight path of the cam-groove the lever will be immovable, which 60 position it will occupy while the push-rod is being retracted into normal position. The slide *d* is given a forward and partial backward movement, while the push-rod *r* is im-

movable. While the slide *d* is on the latter 65 part of its reciprocatory movement, the push-rod *r* is given a forward and backward movement. The lever *y* standing still while the slide *d* moves forward allows the links to be moved in front of the dog carried by said 70 push-rod. The push-rod *r* is constructed with a recess (indicated at 15) and with a shoulder, (indicated at 16,) the recess allowing the adjacent end of the link to drop over thereinto and against said shoulder. The 75 shoe *h* is preferably made detachable from the slide *d*.

The object of employing the cylinder *i* is to simplify the construction of the machine and to hold the link in its true position to be 80 forced by the plunger upon the preceding link. It will be observed that the path of the cross-head *e* is covered laterally by the plates 17 and 18. The guideway *c* is also provided with guide-plates 19 and 20, while 85 the way for the push-rod *r* is also provided with guide-plates 21 and 22. I provide also an adjusting-screw 23 to limit the movement of the link into the path of the guideway *c*, the said screw being provided with a lock-nut 90 24, whereby it may be held in any given position.

While the link is preferably fed from the runway with the hooked end down and with the hook opening on the under side, I do not 95 limit myself solely thereto. The runway is preferably set at a suitable incline. The shoe *h* is preferably made of hardened steel to endure the wear. It will be observed that the distance from the center of the hook or 100 from the center of the orifice of the hook is less to the point of the hook than is the distance from the said center in the opposite direction to the outer groove of the hook.

The runway is so constructed that the links 105 can only be fed with their hooks to the position above described, the path of the runway only permitting the hook of the link to be fed thereinto with the extremity of the hook on the under side. This may readily be accomplished by forming the runway with lateral 110 grooves, (indicated at 25,) the groove being so spaced as only to admit the extremity of the hook or the shortest radius of the hook being located on the under side of the grooves. 115

What I claim as my invention is—

In a machine for assembling metallic links the combination of a support, an upwardly-extended runway, arranged to feed the links with the hook end of the link downward, a 120 guideway, a cylinder upon the bed cut away at one side and at one end thereof to receive and hold a link in position, a reciprocatory slide to move a link from the foot of the runway through said cylinder into the path of the guideway and engage the hook end of the link so carried into the guideway with the 125 opposite end of the preceding link, and means

to force the link into the guideway and to simultaneously throw said link into a horizontal position with the hook end foremost, said slide provided with a shoe to contact with the hook end of the link, said runway provided, at its lower end, with a cap for a portion of said cylinder.

In testimony whereof I have signed this specification in the presence of two subscribing witnesses.

MARSHALL F. CAPRON.
